UNITED STATES PATENT OFFICE.

WILLIAM L. WARD, HERBERT D. REMSEN, AND EMILE C. BOERNER, OF PORT CHESTER, NEW YORK, ASSIGNEES TO RUSSELL, BURDSALL & WARD BOLT AND NUT CO., OF PORT CHESTER, NEW YORK, A CORPORATION OF NEW YORK.

NUT-MAKING MACHINE.

1,203,822.

Specification of Letters Patent.

Patented Nov. 7, 1916.

Original application filed June 27, 1910, Serial No. 569,053. Divided and this application filed April 27, 1912. Serial No. 693,604.

To all whom it may concern:

Be it known that we, WILLIAM L. WARD, HERBERT D. REMSEN, and EMILE C. BOERNER, citizens of the United States, residing at 5 Port Chester, in the county of Westchester and State of New York, have invented certain new and useful Improvements in Nut-Making Machines, of which the following is a full, clear, and exact description, such as 10 will enable others skilled in the art to which it appertains to make and use the same.

This invention relates to means instrumental in the production of nut blanks from stock bars, such as that disclosed and claimed 15 in a co-pending application, filed June 27, 1910, Serial No. 569,053, patented February 24, 1914, No. 1,088,192, of which this application is a division, and the subject-matter herein claimed refers more especially to the 20 mechanism used for feeding the stock bar to the first acting punches which divide the same into a multiplicity of blanks.

As introductory to a more detailed discussion of the essentially novel features, arrangements and combinations underlying the commercial utility of this apparatus, it may be preliminarily noted that, for various reasons known to those skilled in this art, it is desirable to produce nut-blanks from 25 commercially available stock bars of an inexpensive character by operations effected under normal temperatures and without the necessity of shaping the material while in a highly heated condition. The rapid production of high grade hexagonal nut blanks from 30 such an ordinary stock bar by means of an essentially automatic unitary apparatus, as free as possible from delicate, involved or 35 awkwardly related parts or sub-mechanisms, and requiring but little attention, has been 40 the goal for which those commercially engaged in the art of making nuts have long striven. It is exceedingly desirable that such automatic machinery as may be invented 45 for doing this shall be as simple, compact and serviceable as possible, and to attain this end the various component mechanisms or sub-combinations thereof should be devised especially for close relationship and 50 mutual coaction with the other elements of the machine.

Now, this invention has in contemplation an automatic feed mechanism which not only constitutes a component sub-combination of the general machine, but also embodies numerous features and arrangements enabling it to feed a stock bar in the manner required by the working elements of the machine to attain the greatest efficiency.

A more specific object of this invention is 60 to so construct the mechanism for initially feeding in the stock-bar that the same will not only positively and accurately operate, but also so that it will be a simple matter for the operator to disengage the stock bar 65 whenever, by chance, the mechanism should operate imperfectly or when it is desirable to make a hand adjustment, as at the time a new bar is being introduced into the machine.

Another object is to so devise the stock bar feeder that damaged parts may be readily replaced and adjustments may be made for wear, and to so construct the same that, in case the progress of the stock bar is obstructed and the feed thereof thus prevented, the feeder will not be damaged but merely a 70 readily replaceable safety pin will be sheared.

It is also an object of this invention to employ a horizontally reciprocating vise mechanism for feeding the stock bar and to so arrange and construct a lever for driving the same that the intermediate pivot or fulcrum thereof may be adjustably positioned to vary 85 the stroke of the lever, and also enable the pivotal connection between the lever and the sliding vise mechanism to be adjusted as desired.

Other objects and advantages will be in 90 part pointed out hereinafter and in part rendered apparent by means of the accompanying illustrations.

The invention accordingly consists in the features of construction, combinations of 95 elements and arrangement of parts which will be exemplified in the construction hereinafter set forth, and the scope of the application of which will be indicated in the following claims.

To promote a full understanding as to the manner in which this invention may be car-

ried out, drawings exemplifying a preferred embodiment have been appended as a part of this disclosure, and in such drawings like characters of reference denote corresponding parts throughout the several views, of which—

Figure 1 is a plan view of one corner of the unitary machine showing in detail the construction and arrangement of the stock bar feeder; Fig. 2 is a side elevation of the stock bar feeder looking in the direction of the movement of the stock bar as it is fed into the machine, as indicated by the arrow on said bar shown in Fig. 1; Fig. 3 is a general assembly of the entire machine showing the manner in which the herein described feeding mechanism is combined with and related to the various elements of such machine, and Figs. 4 and 5 are details.

Continuing now by way of a more detailed description, it may be preliminarily stated that the characters of reference used herein correspond with those employed in the parent case for the purpose of facilitating the identification of corresponding elements.

The stock bar feeder consists of a gripping means in the nature of a vise and a translating means for reciprocating such vise. The gripping means comprises a rock lever having an actuating end 14 and an actuated end 10, which latter carries a roller riding within the cam groove 9, (as appears more clearly from Figs. 1 and 2.) As the shaft 6 turns in the direction indicated by the arrow B, the actuated end 10 rocks up and down, and this produces a corresponding movement in the actuating end 14. This lever is pivoted at an intermediate point by means of a pivot bolt 11, which is supported at its outer end by means of an uprising plate 12, which latter plate is bolted to lugs 13 which extend from the main frame of the machine. Mounted on the extremity of the arm 14 of the rocker lever is the toe or bearing piece 15 designed to actuate the cam controlling the bar gripping mechanism. This toe is detachably secured in place, as by means of bolts, so as to enable it to be replaced if unduly worn or injured. As shown, this toe projects through a suitable aperture, indicated by dotted line 26, in a stationary bearing block 25, along which bearing block slides the main piece 20, the top plate 21 and the bottom plate 22 of the bar-feeding mechanism. This aperture, indicated by dotted line 26, is slightly wider than the toe 15, but is considerably higher, so as to enable the toe 15 to travel vertically up and down during the operation of the gripping mechanism. The toe 15 passes through the stationary bearing block 25 and enters a horizontally elongated recess, indicated by dotted line 27

(see Fig. 2), in the sliding main piece, or block 20 forming a main part of the feeding mechanism. Inasmuch as this block, or member 20 must be capable of reciprocating or translating horizontally a distance equal to that of the feed of the stock bar, the recess indicated by dotted line 27 will be sufficiently long horizontally to avoid interference with the rounded extremity 16 of the toe 15. This extremity 16 resembles in shape a wide gear tooth and closely interfits within an open channel horizontally formed in a vertically reciprocating cam 17. This cam or bearing piece is carried by the block 20 and is capable of moving up and down, as indicated by the arrows D, independently of the position of the block 20; but on the other hand it is positively carried in a horizontal direction along with said block 20. To that end the cam 17 provides on either side an elongated guide or gib 18 which secures the cam 17 to the block 20, and yet enables it to freely rise and fall, i. e., slide up and down therein. The cam 17 is relatively narrow, and to enable its engagement with the gearlike extremity 16 of the toe 15 to be maintained, such extremity 16 is fully equal in width to the distance through which the stock bar is fed.

It may here be stated that the recess indicated by dotted lines in the sliding or translating block 20 necessarily exceeds in height the distance through which the cam 17 is reciprocated by means of the toe 15.

The cam portion of the vertically reciprocating cam 17 is indicated by 19 and coöperates with a roller 32 indirectly carried by a swinging massive arm 30. The block 20, as has been stated, reciprocates horizontally and is slidably supported on the guide or bearing block 25. To that end, upper and lower cap plates 21 and 22 are securely bolted to the block 20 by means of bolts 23 and 24, so that these three pieces reciprocate as a unit. Means are provided for adjusting and taking up wear, as clearly appears from Fig. 2.

Extending from the block 20 are two lugs 28, in which is journaled the lever pin 29, which in turn supports the massive swinging arm, or member 30, the members 20 and 30 being thus loosely articulated, so as to enable the latter to have a limited angular movement, as indicated by the arrow E. This movement is utilized in gripping the stock bar and is produced through the instrumentality of the cam 17 and the parts which will now be described.

A block 31 is mounted in a counterpart recess in the lower end of the massive swinging arm 30 and has a certain amount of possible play which is permitted on the one hand by a spring and limited on the other hand by a suitable adjustable stop, preventing the same from protruding too far

under the influence of such spring. This part 31 carries the roller 32 which coacts with the cam 19, and 34 indicates the spring which is housed within a suitable recess 33 and is capable of being adjusted as to tension by means of the screw cap 35. A stem 36 extends from the part 31 and passes freely through the cap screw 35 and is provided externally with a pair of lock nuts 37 so that the outward movement of the part 31 may be positively limited, while the inward movement which necessarily more or less varies in extent, due to irregularities in the stock bar, is taken care of by the powerful 15 spring 34. From this it will be perceived that when the cam 17 is depressed by means of the toe 15, the roller 32 rides up the cam incline 19 and through the pressure of the spring 34 urges the lower end of the 20 member 30 outwardly, and correspondingly urges the upper end of such part 30 in the opposite or inward direction. It is this latter end that is utilized in gripping the stock bar. The upper end of the arm 30 provides 25 two integral lugs 38 and 39, which are spaced apart, as shown. Quite snugly, yet slidably fitting within a recess in the lug 39, is a vise block 41, which is preferably backed by means of a block 42, which in 30 turn is positively positioned by means of the hub 43 of the hand lever 44. The block 42 and the hub 43 provide counterpart cams in their adjacent faces, which cams are clearly illustrated by Figs. 1 and 2 and are 35 so constructed that when the hand lever 44 is swung down so as to rest on the horizontal rest 45, the block 42 will be crowded outwardly, whereas when the arm 44 is moved through 90 degrees, the block 42 may be 40 drawn back somewhat by means of the shaft 46 and the spring 47, thereby easing up the pressure between the vise block 41 and the stock bar. An immovable vise jaw 40 is detachably secured to the top plate 21 in some 45 suitable manner, such as by setting the same in a recess in the top plate 21. By this instrumentality, should it be desired to stop the feeding of the stock bar temporarily without stopping the entire machine, or 50 should it be desired to adjust the extent of entry of the stock bar in the machine (as when a new bar is required), the operator, by lifting the handle 44, can release the vise jaws from the stock bar, irrespective of the 55 position of the feeding mechanism, and thereupon the freed stock bar can be manually adjusted in position. Upon turning the handle 44 to its normal position, the machine will be ready to resume its cycle of 60 operations.

The feeding means for horizontally reciprocating the vise-bearing top plate 21 will now be described. It may here be noticed that it is highly desirable to so construct 65 and arrange the elements controlling the re-

ciprocations of the stock-bar vise, as to enable adjustments to be easily made whereby the extent and periodicity of the automatic feed may be regulated and accurately determined. To that end, this invention proposes a multi-part lever 48, which at one end carries the roller 49 which coacts with the circumferential cam 8. This lever is pivotally supported at an intermediate point and has its free end, so to speak, connected 70 with the top plate 21 of the feeding structure. The relation between these three points will determine the character of the feed and therefore means have been adopted to enable this relation to be varied within 75 reasonable limits. Thus, the bolt 50 constitutes the intermediate pivot or fulcrum of the lever 48, but this bolt is so arranged and constructed as to be capable of being secured in various positions. This construction 80 is very clearly shown in Figs. 4 and 5, from which it will be seen that the lower end of the bolt passes through a shelf-like portion 13' extending from the main frame of the machine. This portion 13' is provided 85 with a rectangular recess into which is fitted the block 50' and below this block is located the slot 55' through which the shank of the bolt 50 passes. A nut 50' serves to lock the bolt and block in position against 90 movement. For the purpose of facilitating adjustment, the adjusting bolt 50''' is provided and said bolt is rotatably mounted in the frame portion 13' and has a screw-threaded shank in engagement with the block 50'', so that by turning the bolt said block 95 may be shifted in position. The upper end of the bolt 50 passes through a detachable lug 51 which is in turn adjustably secured to the main frame by means of bolts 52 100 passing through suitable slots shown more clearly by Fig. 1. In this way the position of the bolt 50 with respect to the main frame may be varied at will. The lever 48 is also adjustably mounted in the saddle 105 block 53 by means of bolts 54 which are adapted either directly or through the instrumentality of an insert-piece, to clamp the snugly fitting part 55 of the lever 48 in a corresponding aperture in such block 53. It 110 is to be understood that the pivot bolt 50 has its bearing directly on the swinging block 53 and passes through the elongated aperture, indicated by dotted lines 55' in Fig. 1. From this, it will be readily understood 115 that the exact position of the pivot bolt 50 may be very readily secured.

At this point attention is directed to a safety appliance employed in connection with the feed mechanism. It may occasionally happen that either because of a failure to sufficiently clear away the metal cut from the forward end of the stock bar, or for other reasons, the forward progress of the stock bar will be unduly or even posi- 125 130

tively obstructed, and to prevent the feeding mechanism from being damaged or fractured by reason of its inability to advance the stock bar, this invention contemplates so constructing the lever 48 that a suitably positioned safety pin, amply strong for all ordinary purposes, will be sheared and thus prevent rupture of this lever or other element of the feed mechanism. To that end, the forward or actuating end of the lever 48 terminates somewhat short and extends in the form of the extension piece 56, which is pivoted to the same by means of a strong bolt 57. A clamping block 58 which engages a circular lip 59 which is integral with the forward end of the lever, also assists in positioning these parts. Adjacent the extremity of the forward end, is an aperture 49' which enlarges toward the under surface of such part and is in registry with the corresponding aperture in the extension piece 56. A safety pin 49'' fits in and is retained by these alined apertures, so that in case the pressure becomes at any time excessive, this pin may be readily sheared and may then be replaced by a duplicate part. This invention also embodies means for adjusting the relative position of a pivot bolt 60 which is directly instrumental in connecting the sliding vise block 21 with the actuating lever. The extension piece 56 is provided with a square recess adjacent its end, within which is adjustably positioned a block 62 which is clamped in place by means of the nut 61 on the pivot bolt 60. It will from this be readily perceived that it is a very simple matter to so adjust the lever 48 as to feed the vise block 21 and its associated parts through any desired feed spacing.

The operation of the stock bar feed mechanism will be obvious from the foregoing, but may be briefly recapitulated as follows: Assuming the parts to be in the position shown by Fig. 1, in which the stock bar feeder is in the advanced position, the further rotation of the main shaft 6 will raise the lever end 14, thus uplifting the cam 19 and permitting the arm 30 to swing back to ease up the clamping pressure on the stock bar. The circumferential cam 8 is so designed that the roller 49 will now be caused to move toward the frame of the machine so as to swing the other end of the lever 48 in the opposite direction and thereby move the released gripping vise along the stock bar a distance corresponding to the length of a blank. During this withdrawal of the vise the stock bar is not moved, but at the end of the backward stroke the cam 9 operates on the lever arm 10 to actuate the part 18 and thus cause the cam 19 to outwardly move the roller 32 and swing the arm 30 into a position adapted to grip the stock bar. Thereupon the circumferential

cam 8 acts on the roller 49 to swing the lever 48 in a direction such that the vise will be advanced as indicated by the upper head of the arrow C, and thus feed the stock bar into the machine a distance corresponding to the length of a nut blank. This brings the end of the stock bar opposite the shearing-off punch 1', so that as the latter now advances a nut blank will be sheared from the end of the stock bar. It will be noticed that this shearing-off punch extends forwardly some little distance beyond the forward extremity of the perforating punch 2', so that the shearing-off punch will perform its function just before the perforating punch operates. When the perforating punch advances to perforate the stock bar near its end, it may be observed that the stock bar is deformed and elongated through the action of the perforating punch to an extent sufficient to cause the end of the stock bar to bind unduly against the shearing-off punch during the withdrawal of the latter. It will be understood that the shank of the shearing-off punch is slightly undercut and that this binding action would take place near its head. To prevent this action, however, this invention proposes a construction whereby the stock bar is retracted a slight distance just after the perforating punch has been withdrawn, thereby affording a free withdrawal of the shearing punch. This is accomplished by providing the circumferential cam 8 with a slight undercut 8' so that the roller 49 will be given a slight movement toward the frame of the machine just after the perforating punch has been withdrawn, thereby effecting a slight retraction of the stock bar during the withdrawal of the shearing-off punch.

From the foregoing it will be perceived that this invention effectively achieves several objects and advantages above outlined, and that as a result thereof a unitary feeding mechanism is rendered available which may be utilized in various connections, and especially in the relationship outlined with respect to the general machine shown by Fig. 4.

Having described our invention, what we claim as new and desire to secure by Letters Patent is:—

1. A mechanism of the nature disclosed, comprising an elongated frame member, a jaw-supporting member arranged to slidably reciprocate horizontally on said frame member, a jaw-carrying arm hinged to said jaw-supporting member about an axis in parallelism with the movement of said jaw-supporting member, a lever terminating at one end in a horizontally elongated bearing piece adapted to swing up and down with said lever, a cam in engagement with said bearing piece and said arm whereby the same may be oscillated with the rise and fall

of said bearing piece, and means for reciprocating said jaw-supporting member and oscillating said lever at appropriate periods.

2. A mechanism of the nature disclosed, comprising a drive shaft, a face cam arranged on one end thereof, a circumferential cam arranged adjacent said face cam, a lever horizontally oscillated by said circumferential cam, a jaw-carrying member horizontally reciprocated by said lever, a second lever vertically oscillated by said face cam, and means actuated by said second lever to enable a stock bar to be clamped and advanced during a forward reciprocation of said member, said bearing piece engaging said cam throughout the reciprocatory path of said jaw-supporting member.

3. A mechanism of the nature disclosed, comprising a member adapted to reciprocate in a horizontal direction, a jaw carried thereby, a second member pivoted to said reciprocating member about an axis parallel with the direction of movement of said reciprocating member, a jaw carried by said second member, a spring-pressed part carried by said second member, a cam mounted to vertically move in said reciprocating member and adapted to actuate said second member through said part to cause said jaws to move into gripping position, a vertically oscillating arm terminating in a horizontally elongated bearing piece having a sliding bearing with said cam, and means for reciprocating said first mentioned member and vertically oscillating said last-mentioned lever.

4. A mechanism of the nature disclosed, comprising a vise mechanism adapted to be reciprocated in a horizontal direction, a power shaft having a circumferential cam, a lever connected at one end to said vise mechanism and at the other end coöperating with said circumferential cam, an intermediate fulcrum bolt, adjustable mountings for said fulcrum bolt, a block having a pivotal relation with said fulcrum bolt, and means for adjustably securing said lever to said block.

5. A mechanism of the nature disclosed, comprising a drive shaft, a circumferential cam thereon, a lever coöperating at one end with said cam, a pivot adjustably secured to said lever at an intermediate point, adjustable bearings for said pivot, an extension piece adjustably secured to the free end of said lever, a vise mechanism adapted to be reciprocated, and an adjustable bearing connecting said vise mechanism with said extension whereby the former may be actuated by the latter.

6. A mechanism of the nature disclosed, comprising a reciprocating vise mechanism, a drive shaft having a cam, a lever oscillated by said cam, a rocking block slidably engaging with an intermediate portion of

said lever, means for locking the two together, an adjustably positionable pivot block journaled in said rocking block, and adjustable means connecting said vise mechanism with said lever.

7. A mechanism of the nature disclosed, comprising a reciprocating vise mechanism, a drive shaft carrying a cam, a lever arm having one end connected with said cam and adjustably pivoted at an intermediate point, an extension piece overlapping and bolted to one end of said lever, a clamping piece bolted to said extension piece and overlapping an end lip of said lever, and means adjustably pivoting said extension piece to said reciprocating vise mechanism.

8. A mechanism of the nature disclosed comprising a pair of jaws for gripping stock, automatic means for bringing said jaws into gripping contact with said stock, means for moving said jaws to advance said stock a predetermined distance, means for automatically moving said jaws to retract said stock a short distance, and means for thereafter releasing said jaws and retracting the same a predetermined distance preparatory to again gripping and advancing said stock.

9. A mechanism of the nature disclosed comprising, in combination, a bearing block, a pair of loosely articulated members movably supported by said bearing block, means adapted to reciprocably translate said members, gripper jaws on said respective members, means adapted to cause relative approaching movement of said gripper jaws comprising a cam movably mounted on one of said members, a spring adapted to transmit pressure from said cam to one of said jaws, and independent hand-controlled means adapted to cause relative separating movement between said jaws.

10. A mechanism of the nature disclosed comprising, in combination, a bearing block having a transverse aperture, a pair of loosely articulated members movably supported by said bearing block, one of said members having a recess opposite said aperture, means adapted to reciprocably translate said members, gripper jaws on said respective members, means adapted to cause relative approaching movement of said gripper jaws comprising a cam reciprocably mounted on said recessed member, a rock lever having one end projecting through said aperture into said recess, and connections between said end and said cam whereby the latter is positively moved by said lever in each direction of said latter's reciprocation.

11. A mechanism of the nature disclosed comprising, in combination, a bearing block, a pair of loosely articulated members movably supported by said bearing block, means adapted to reciprocably translate said mem-

bers comprising a rock lever, gripper jaws on said respective members, means adapted to cause relative approaching movement of said jaws comprising a cam movably mounted on one of said members, a spring adapted to transmit pressure from said cam to one of said jaws, adjustable mountings for the fulcrum of said lever, and an adjustable pivotal connection between said lever and one of said articulated members, said lever comprising portions connected by a frangible pin adapted to give way under abnormal strain against the reciprocation of said members.

12. A mechanism of the nature disclosed comprising, in combination, a bearing block, a pair of loosely articulated members movably supported by said bearing block, gripper jaws on said respective members, means adapted to cause relative approaching movement of said jaws transversely of the direction of movement of said members on said block comprising a cam mounted on one of said members to move transversely of the direction of the movement of said members on said block, a spring adapted to transmit pressure from said cam to one of said jaws, a drive shaft, circumferential and face cams thereon, and rock levers operatively connected to said last-mentioned cams and to one of said members and said first-mentioned cam, respectively.

13. A mechanism of the nature disclosed comprising, in combination, a bearing, a pair of pivotally connected members mounted to reciprocate on said bearing, gripper jaws on the respective members, and means adapted to cause relative pivotal movement of said members comprising a relatively movable cam on one member, a bearing piece on said other member with which said cam is adapted to contact, a spring between said bearing piece and said other member and an adjustable stop adapted to vary the position of said bearing piece relatively to said cam.

14. A mechanism of the nature disclosed comprising, in combination, a bearing, a pair of pivotally connected members mounted to reciprocate on said bearing, gripper jaws on said respective members, one of said jaws being movable relative to its respective member, manual means adapted to be positioned to fix said jaw against movement relative to its respective member away from said other jaw and to permit such movement, and means adapted to cause relative pivotal movement of said members comprising a relatively movable cam on one member, a bearing piece on said other member with which said cam is adapted to contact and a spring between said bearing piece and said other member.

15. A mechanism of the nature disclosed comprising, in combination, a bearing, a pair of pivotally connected members mounted to

reciprocate on said bearing, gripper jaws on said respective members, one of said jaws being movable relative to its respective member, manual means adapted to be positioned to fix said jaw against movement relative to its respective member away from said other jaw and to permit such movement, spring means adapted to move said jaw relative to its respective member in a direction away from said other jaw in a predetermined position of said manual means, and means adapted to cause relative pivotal movement of said members comprising a relatively movable cam on one member, a bearing piece on said other member with which said cam is adapted to contact and a spring between said bearing piece and said other member.

16. A mechanism of the nature disclosed comprising, in combination, a bearing, a pair of pivotally connected members adapted to reciprocate on said bearing, one of said members providing a gripper jaw, a guide on said other member, a gripper jaw movable in said guide, a lug on said latter member spaced from said guide, a hub rotatably mounted between said lug and said movable gripper jaw, said hub having a cam face adapted to urge said movable jaw toward said other jaw, and means adapted to cause relative pivotal movement of said members.

17. A mechanism of the nature disclosed comprising, in combination, a bearing, a pair of pivotally connected members mounted to reciprocate on said bearing, gripper jaws on said respective members, and means adapted to cause relative pivotal movement between said members comprising a relatively movable cam on one member, a roller on said other member with which said cam is adapted to contact and a spring between said roller and said other member.

18. A mechanism of the nature disclosed comprising, in combination, a pair of pivotally connected members, gripper jaws on said respective members, means adapted to reciprocably translate said members, a cam relatively reciprocably mounted on one member adapted by said relative reciprocal movement to cause said jaws to approach and permit them to recede from each other, a lever so operatively connected to said cam as to positively cause said relative reciprocal movement, and means adapted to oscillate said lever.

19. A mechanism of the nature disclosed comprising, in combination, a pair of pivotally connected members, gripper jaws on said respective members, means adapted to reciprocably translate said members, a cam relatively reciprocably mounted on one member adapted by said relative reciprocal movement to cause said jaws to approach and permit them to recede from each other, and means adapted to cause said reciprocal move-

ment of said cam comprising an oscillatory lever and a toe and channel engagement between said lever and said cam.

20. A mechanism of the nature disclosed 5 comprising, in combination, a pair of pivotally connected members, gripper jaws on said respective members, means adapted to reciprocably translate said members, a cam relatively reciprocably mounted on one of 10 said members adapted by said relative reciprocal movement to cause said jaws to approach and permit them to recede from each other, and means adapted to cause said reciprocal movement of said cam comprising 15 a lever and a toe and channel engagement between said lever and said cam, one of said toe and channel-engaging elements being co-extensive with the amplitude of translation of said members.

20. 21. A mechanism of the nature disclosed comprising, in combination, a bearing block, 25 a pair of loosely articulated members movably supported by said bearing block, means adapted to reciprocably translate said members, gripper jaws on said respective members, means adapted to cause relative approaching movement of said gripper jaws comprising a cam movably mounted on one

of said members, a spring adapted to transmit pressure from said cam to one of said 30 jaws, and independent hand-controlled means adapted to cause relative separating movement between said jaws.

22. A mechanism of the nature disclosed comprising, in combination, a bearing block, 35 a pair of loosely articulated members movably supported by said bearing block, means adapted to reciprocably translate said members, gripper jaws on said respective members, means adapted to cause relative approaching movement of said gripper jaws comprising a cam reciprocably mounted on one of said members, a rock lever, and connections between said cam and lever comprising a toe on one and a channel in the 40 other whereby the cam is positively moved by said lever in each direction of said latter's reciprocation.

In testimony whereof we affix our signatures in the presence of two witnesses.

Copies of this patent may be obtained for five cents each, by addressing the "Commissioner of Patents, Washington, D. C."

It is hereby certified that in Letters Patent No. 1,203,822, granted November 7, 1916, upon the application of William L. Ward, Herbert D. Remsen, and Emile C. Boerner, of Port Chester, New York, for an improvement in "Nut-Making Machines," errors appear in the printed specification requiring correction as follows: Page 5, line 3, claim 1, strike out the period and insert a comma and the words *said bearing piece engaging said cam throughout the reciprocatory path of said jaw-supporting member.*; same page, line 15, claim 2, strike out the comma and insert a period, and, same line and claim, commencing with the word "said" strike out all to end of claim; and that the said Letters Patent should be read with these corrections therein that the same may conform to the record of the case in the Patent Office.

Signed and sealed this 16th day of January, A. D., 1917.

[SEAL.]

F. W. H. CLAY,

Acting Commissioner of Patents.

Cl. 10—162.
